ABSTRACT: In accordance with my invention a strap is adapted to be detachably secured to the shoulder of a wearer and worn under a coat or jacket. The strap extends downwardly toward the waist and at its lowest point is provided with one or more fastener means. A purse, which can be hand carried in conventional manner, is provided with a like plurality of fastening means which are adapted for detachable engagement with the fastener means. As a result, the purse can be held next to the waist by the straps, out of sight, and inaccessible to would-be thieves and purse snatchers.

INVENTOR.
STELLA M. SCHROEDER

CONCEALED PURSE: HIDE-A-PURSE**SUMMARY OF THE INVENTION**

In accordance with my invention a strap is adapted to be detachably secured to the shoulder of a wearer and worn under a coat or jacket. The strap extends downwardly toward the waist and at its lowest point is provided with one or more fastener means. A purse, which can be hand carried in conventional manner, is provided with a like plurality of fastening means which are adapted for detachable engagement with the fastener means. As a result, the purse can be held next to the waist by the straps, out of sight, and inaccessible to would-be thieves and purse snatchers.

BRIEF DESCRIPTION OF THE DRAWINGS

In the drawings:

FIG. 1 is a perspective view of my invention in use;

FIG. 2 is a detail view of a portion of the strap;

FIG. 3 is a detail front view of the purse with an engaged portion of the strap;

FIG. 4 is a side view of the structure shown in FIG. 3; and

FIG. 5 is a view similar to FIG. 3 but showing the parts detached.

DETAILED DESCRIPTION OF PREFERRED EMBODIMENTS

Referring now to FIGS. 1-5, a shoulder encircling strap 10 has a buckle 12 at one end and buckle engaging holes 14 at the other end whereby the strap can form a closed loop variable in size.

The lowest portion of the strap which extends to the waist of a wearer along side the shoulder about which the strap does not extend, i.e., the strap extends from one shoulder to a position at the waist below the other shoulder, is provided with three downwardly extending parallel fingers 16, each finger having at its free end a separate female fastener 18.

A purse 20 is provided adjacent the top edge on one surface three male fasteners 22. Each male fastener 22 is adapted to be engaged with a corresponding female fastener 18 whereby

the purse can be held underneath a jacket or coat secured to the strap as described.

If desired, the male and female fasteners can be disengaged, and the purse carried separately in conventional exposed manner.

While I have described my invention with particular reference to the drawings such is not to be considered as limiting its actual scope.

I claim:

1. An improved strap supported purse, comprising
  - a. an elongated flat shoulder strap,
  - b. buckle means adjustably connecting the opposite ends of said flat shoulder strap, into a closed loop of adjustable circumference,
  - c. a plurality of flat, integral suspending means depending in predetermined uniform spacing and in parallel relationship from a lower edge of said strap,
  - d. said flat integral suspending means extending for a predetermined length and in the plane of said strap,
  - e. each of said suspending means including therein adjacent to the end thereof a first fastening means,
  - f. a purse means, having at least front, rear, side, and bottom walls,
  - g. a plurality of second fastening means equal in number of said plural first fastening means
  - h. said second fastening means being carried by said front wall in the identical spacing of that of said first fastening means and being arranged along an axis below and generally parallel to the upper edge of said front wall,
  - i. said first and second fastening means comprising a plurality of pairs of fastening means,
  - j. each of said pairs of fastening means comprising a male element and a female element matable therewith,
  - k. said axis being spaced below said upper edge of said purse a distance substantially equal to, and not greater than, the length of said suspending means, and
  - l. said purse thereby being detachably supported from said strap immediately adjacent to the lower edge thereof in a manner whereby said purse and said strap are substantially nested.
